WHEEL SPINNER

Marcellus Samuel Merrill and Lowell H. Erickson, Denver, Colo.; said Erickson assignor to said Merrill
Application March 27, 1953, Serial No. 344,991

7 Claims. (Cl. 74—16)

This invention relates to spinners for wheels and more particularly one of the heavy duty type for spinning automobile and airplane wheels, by way of example.

One of the objects of my invention is to produce a wheel spinner which can accomplish continuous heavy duty spinning of wheels, yet be easy to operate and transport.

Another object is to produce a heavy duty portable wheel spinner in which the weight thereof can be employed in assisting in holding the spinner pulley engaged with the wheel operated upon, either during spinning or

braking. Yet another object is to produce a wheel spinner which is provided with wheels for easy transporting and with control means for the wheels whereby the spinner can be caused to rest directly on a support surface, such as a floor, with the transporting wheels raised off the support.

A further object is to so construct a spinner of the type referred to having as a part of the control means a swingable handle structure permitting the wheels to be in position for pushing or pulling of the spinner when the handle is in a raised position and permitting the spinner to rest directly on the supporting surface, free of the wheels when the handle is lowered.

A still further object is to so swivel the spinner on a supporting or base plate that the spinner, when positioned for spinning and braking, will rest on the plate and be freely movable by the handle to move the spinning pulley into and out of engagement with the wheel to be rotated and also forced against said wheel by effort of the operator.

Yet a further object is to employ the handle as a switch control member to cause the pulley driving motor to be energized and de-energized during operation.

Another object is to employ the handle to control a brake for the spinning pulley and thus through this pulley cause stopping of the wheel which has been previously spun.

Other objects will become apparent from the following description taken in connection with the accompanying drawings in which:

Figure 1 is a side view of a heavy duty wheel spinner embodying our invention, said view having parts broken away and with only a part of the handle structure being shown, said view showing the spinner being supported on the wheels ready for easy wheeling about as desired;

Figure 2 is a rear view of the wheel spinner being supported on the transporting wheels;

Figure 3 is a top view of the wheel spinner with parts being broken away and the handle in a lowered position so that the spinner rests on its support plate with the transporting wheels off the floor;

Figure 4 is a top view showing the spinner positioned in relation to a front automobile wheel for spinning it so that wheel balancing operations can be accomplished;

Figure 5 is a side view of the spinner when positioned as shown in Figure 4;

Figure 6 is an end view of the spinner when positioned

as shown in Figure 4, said view being from the handle and spinning pulley end;

Figure 7 is a view showing the brake for the spinning pulley and the structure whereby it is actuated by the handle arms;

Figure 8 is a view taken on the line 8—8 of Figure 3 showing details of the switch operating structure and the latch means for holding the spinner supported on the wheels, said view having the handle shaft shown in two dashed line operative positions;

Figure 9 is an end view of the structure shown in Figure 8, said view being taken on the line 9—9 of Figure 3; and

Figure 10 is a sectional view showing the pivotal relation of the spinner motor base member and the supporting or base plate.

The drawings show a preferred construction of the wheel spinner embodying our invention and by reference to Figures 1 and 2 there is provided a base plate P, at the four corners of which are carried rubber pads 10 so as to increase the frictional engagement of the plate with any floor or other supporting surface and thus prevent shifting of the spinner when operating. On the top of this base plate slightly to one side of the center thereof, there is secured by bolts a swivel spindle 11, shown in detail in Figure 10, which is arranged to be received in a swivel collar 12 secured by screws to the underneath surface of a motor base member 13. With the swivel spindle and swivel collar connecting the base plate and the motor base, it will be seen that the motor base can be rotated on the plate about the axis of the swivel collar. Separation of the base plate from the motor base will be prevented by the flange 14 carried by the swivel collar.

On the motor base 13 there is mounted the electric motor M with the drive shaft 15 thereof extending toward the rear of the spinner and carrying a spinning pulley S which, it will be noted, is of considerable diameter and has an outer cylindrical surface of considerable width. The base 13, motor M and the pulley S, together with cooperating structure, thus form a spinning unit rotatable about a generally vertical axis on the base P. The motor base, on opposite sides thereof and at points approximately between the pulley and the motor, carries upstanding brackets 16 and 17, at the upper ends of which are pivot pins 18 and 19 whereby a handle H can be pivoted to the motor base. It will be seen that this handle H is of general U-shaped construction having two shafts 20 and 21 of tubular construction connected together at one end by a curved tubular section 22. Near the lower ends of the shafts and spaced therefrom are welded bearing sleeves 23 and 24 to receive the pivot pins 18 and 19, all as best seen in Figure 7.

On the unconnected ends of the two shafts of the handle there are carried outwardly extending spindles 25 and 26 and rotatably mounted thereon are wheels 27 and 28 which are controllable by the handle and employed for transporting the spinner from one place to another. Because the wheels are mounted at the extreme ends of the two handle shafts beyond the pivots thereof, it is seen that by raising up on the curved end of the handle to cause the wheels to be engaged with any floor or supporting surface, then the motor and spinning pulley can be raised to these members, together with the base plate, are all supported on the wheels.

In order to maintain the handle in its upward position, as shown in Figures 1 and 2, so the plate P is off the floor and the entire spinner is supported wholly on the wheels, there is provided a latch means between the handle and the motor base. This latch means is best shown in Figures 3, 8 and 9. The motor base has an upward flange and on the side of the handle shaft 20 carries a block 29 and on the opposite side of the motor base adjacent the shaft 21 is a similar block 30 secured to a flange of the

motor base. The blocks are set at an angle, as can be seen in Figure 8. As best shown in Figure 3, the handle shaft 20 carries a latch member 31 for cooperation with block 29. The latch member has a portion which slides in the tubular member and an extension which projects outwardly through a slot in the shaft so as to cooperate with the latch block 29. The latch block has secured thereto an actuating rod 32 which extends upwardly through the tubular shaft toward the curved connecting section 22 of the handle. Near this connecting section is a knurled actuating sleeve 33 which is slidable on the exterior of the shaft 20 and of sufficient length to be grasped by the full hand of an operator. The sleeve is connected to the rod within the tube by a connecting structure 34 which is arranged to slide in a slot in the shaft whenever the sleeve is moved longitudinally. Thus, it will be seen that an outward pull on the sleeve 33 can actuate the latch member 31 at the lower end of the shaft. In order that the latch member may be normally biased to a position where it will engage beneath the lower end of the latch block 29, a spring 35 is provided in surrounding relation to the rod 32 and is arranged to be interposed between the latch and a block 36 positioned within the shaft and fixed thereto and through which the rod 32 can slide.

Also carried by the lower end of the shaft 21 of the handle is a latch 37 for cooperation with the latch block 30 carried by the motor base adjacent the shaft. This latch block is arranged to be actuated by structure which is the same as that already described. Connected to the latch block is a rod 38 which extends upwardly through the shaft and is joined to a knurled sleeve 39 slidable on the outside of the shaft by a connecting means 40. The latch member is biased downwardly to a position where it can engage beneath the latch block by spring structure (not shown) which will be the same as the spring structure employed with the latch 31.

With the described latch means carried by the lower end of each shaft of the handle, it will be seen that if the end connecting section of the handle is moved upwardly to the raised position shown in Figures 1 and 2, the two latches will move downwardly and engage beneath the lower ends of the angular latch blocks, all as illustrated by the long dashed lines in Figure 8. Due to the angular position of the latch blocks, it will be seen that as the handle is raised and the wheels caused to engage with the floor and then the motor, spinner pulley and base plate raised upwardly off the floor, the latches will slide downwardly on the sides of the latch blocks and be caused to move upwardly in the handle shafts, thereby compressing the springs which act upon the latches. When the handle reaches such a position that the latches are free to move past the end of the latch blocks, the springs will cause them to snap to this position and thus the handle will be locked and maintained in its up position with the spinner being supported only on the wheels for easy transporting.

Whenever it is desired to lower the spinner and cause it to raise on the floor through the base plate only, then it is only necessary for the operator to grasp both the knurled sliding sleeves on the upper ends of the two handle shafts and pull them toward the curved section of the handle. This will pull the latches to positions where they no longer will be engageable with the lower ends of the latch blocks and the handle can then be allowed to move downwardly, with the result that the base plate will be brought into engagement with the floor and the spinner will be supported solely on this base plate. The wheels are then free of the floor. With the spinner thus resting on the base plate, the motor base, motor and the spinning pulley can then be swiveled around on the base plate as desired, merely by swinging the handle, since this handle has its two shafts connected to the motor base on opposite sides thereof.

We have also found it desirable to have the starting

and stopping of the motor controllable by the handle. This is accomplished when the handle means is in the lower position where the spinner base plate is resting on the floor. For simplicity, we operate the starting and stopping switch of the motor by the latch 37 carried on the shaft 21 of the handle. Referring now to Figures 1, 8 and 9, the side flange of the motor base 13 has pivoted thereto a lever 41 which will have at its rear end an L-shaped portion 42 to lie over the base flange just forwardly of the latch block 30 and so arranged that the latch 37 can be positioned above the L-shaped extension when the handle is lowered to bring the wheels off the floor. The front end of the lever 41 lies alongside of another arm 43 which will be pivoted on the end of a shaft 44 carried by the front of the motor base. The forward end of lever 41 terminates slightly to the rear of shaft 44 and is connected to the forward end of arm 43 through a spring 45, which spring will be employed to actuate the arm 43 whenever the lever 41 is actuated. The shaft 44 extends beneath the switch 46 of the motor which is enclosed within a suitable switch box. The end of the shaft 44 also has secured thereto a short arm 47 which is pivotally connected to a link 48 that operates the switch.

When the handle is in the down position, as shown by the short dashed lines in Figure 8, the switch will be in its "off" position and it will be held there by the operation of a spring 49 acting upon the underneath side of the L-shaped flange 42 of the lever 41, said spring being enclosed within a cylinder member 50 attached to the flange of the motor base. If, under these conditions with the latch 37 overlying the L-shaped end of the lever 41, the curved section end of the handle should be raised, the latch 37 will move downwardly and swing the lever 41 in a counterclockwise direction as viewed in Figure 8, thereby raising up the front end of the lever 41. The upward movement of this lever 41 will, through the spring 45, then operate the arm 47 and link 48 and throw the switch to the "on" or "closed" position, thereby starting the motor. By lowering the curved end of the handle and raising the latch 37, the switch will automatically be "opened" by the upward movement of the lever 41 under the action of the spring 49.

Electrical power for operating the motor will be brought in through the forward end of the spinner by means of a suitable electrical cord 51 connected through the switch to the motor, as shown in Figure 1. This cord will be of considerable length and in order that it may be readily carried with the spinner when it is desired to transport the spinner, the two shafts of the handle are provided with hooks C upon which the cord can be looped. A suitable removable cover 52 will be provided to enclose the switch and part of the operating mechanism for controlling the switch.

For convenience of operation, we also employ the handle to actuate a brake for the spinner pulley, so when the motor is cut off the spinner pulley can be braked and therethrough brake any wheel that has been spun. The inside of the spinning pulley, as best shown in Figures 3 and 7, will act a brake drum with which can engage a brake shoe 53. The central part of the shoe is pivotally mounted on a pin 54 which extends laterally from the central part of a horizontal brake actuator rod 55 positioned just rearwardly of the pulley and near the lower side thereof. This rod is of such length that its ends will be in a position to be engaged by the shafts 20 and 21 of the handle upon lowering thereof. Thus, by moving the handle down, the brake shoe can be brought into engagement with the inner surface of the spinning pulley, all as illustrated in Figures 5 and 7. To carry the rod 55 on the motor base plate and yet permit it to be actuated by the handle, the two ends of the rod just inwardly of where the ends will be engaged by the handle shafts are provided with forwardly extending arms 56 and 57. As best shown in Figures 1 and 7, each of these arms carries space

bolts 58 and 59 which extend downwardly through an extension of the motor base and are provided with heads positioned therebeneath. Between the bolts is a spring 60 which acts upwardly on the arm, said spring being carried in a cylindrical member 61 mounted on the motor base.

With this arrangement, the arms and rod 55 will normally be pushed upwardly to the limit permitted by the engagement of the heads of the bolts 58 and 59 with the motor base. Under such conditions, the brake shoe will be held disengaged from the spinning wheel. However, if the handle H is swung downwardly so the two shafts can engage the ends of the rod 55 for operating the brake, these ends are free to move downwardly as the bolts will slide in the motor base. As a result, the brake shoe will be brought into engagement with the inside of the spinning wheel and braking action will take place. When the brake is operated, the two springs 60 will be compressed and upon raising the handle the springs will automatically move the actuator rod 55 upwardly and bring the brake shoe away from the inside surface of the spinning wheel.

From the foregoing description of the details of our heavy duty wheel spinner, it will be seen that the spinner can be transported about on wheels as desired and in an easy manner. The wheels will be caused to rest on a floor or other supporting surface and the entire spinner structure including the motor spinner wheel supported solely on the wheels by merely raising the curved end of the handle to its "up" position where the latches engage beneath the latch blocks in a manner indicated in the long dashed lines of Figure 8 and also shown in Figures 1 and 2. When it is desired to use the spinner to spin an automobile wheel, for example, the spinner will be transported to a position adjacent the wheel such as, for example, the front wheel W illustrated in Figure 4 which can be turned at an angle from the straight ahead position so it will be more convenient to bring the spinning pulley into engagement with the wheel. In placing the spinner for operation, it will be so placed that the longitudinal axis of the spinner, that is, the axis of the spinning pulley and the motor, will be at less than a right angle with the plane of the wheel and with the spinner close to the wheel. With the spinner in this position, it will then be caused to rest on the floor by the base plate only and the wheels lifted off the floor, such position being shown in Figure 5 of the drawings. It will be noted that when the base plate is fully engaged with the floor and all the weight of the heavy motor and spinning pulley thereon, the rubber pads will give good frictional engagement so that moving of the spinner on the floor will be difficult. When the wheels are raised, the handle will come into the position shown in Figures 5 and 6. To accomplish lowering of the spinner so the base plate will engage the floor, it will be noted that all that need be done is place the hands on the knurled sleeves 33 and 39 carried by the handle shafts and pull these toward the curved end section of the handle, which will also be toward the operator as he stands at the curved end of the handle. This pulls the latches from beneath the latch blocks and then the spinner, including the base plate, can be allowed to move downwardly to rest position by slowly lowering the handle toward its horizontal position shown in Figure 5. After lowering of the handle, the knurled sleeves are released and this then causes the latch 37 to assume a position over the end of lever 41 so that the motor switch can be controlled.

Before the spinning pulley is caused to rotate by operation of the motor, it will be brought into engagement with the tread surface of the tire on the wheel and this is accomplished by merely swinging the motor and the spinning pulley on the base plate. The arrow 63 in Figure 4 illustrates the direction of movement of the handle to bring about frictional engagement between the spinning pulley and the tire tread. The motor is now caused to be started by raising up on the curved end, all as previously described and illustrated by the arrow 62 and the

upper dashed lines. As the motor comes up to speed and the spinning of the wheel takes place, the spinning pulley can be maintained in tight driving engagement with the tire tread by continued force applied to the handle in the direction of the arrow 63. To disengage the spinning pulley from the wheel, the handle need only be moved in the reverse direction shown by the arrow 64 in Figure 4. With the wheel W spinning, its unbalance can be determined by known methods and during such the motor can be stopped by permitting opening of the switch, such resulting when the handle is allowed to move to the full line position shown in Figure 5 and also the position shown in short dashed lines in Figure 8. If it is desired to stop the spinning wheel quickly after unbalance is determined, the pulley S will be engaged with the tire and the brake will be applied by pushing downwardly on the curved end of the handle, as indicated by the arrow 65 and the lower dashed lines in Figure 5.

After the spinning and braking operations on the wheel are completed, the wheel spinner can be again supported solely on the wheels and moved to any desired place. This is accomplished by pulling the latch 37 back so as to be free of the end of lever 41 and then raising up on the curved end of the handle. The wheels at the other end of the handle will then be lowered to engage the floor and as continued upward movement of the curved end of the handle takes place, the motor spinning pulley and the base plate will all be lifted up off the floor with the wheels acting as a fulcrum point. During upward movement of the curved end of the handle, the latches will slide down the sides of the latch blocks and when the handle reaches a position where the latches are beyond the lower ends of the blocks, they will, under spring action, move beneath the ends of the blocks and thereby lock the handle so as to maintain the motor and spinning pulley together with the base plate supported on the wheels. Transporting can then be easily accomplished by pushing on the handle.

From the foregoing description it will be seen that our improved heavy duty spinner is simple in construction and easily operable. All conditioning of the spinner for transporting, positioning for spinning operations, causing it to rest on the floor by the base plate, together with the starting and stopping of the motor and the braking of the spinning pulley, is accomplished by movement of the handle or by control means on the handle. Engagement between the spinning pulley and the wheel to be spun is easily accomplished and controlled as desired by manipulation of the handle. Notwithstanding the fact that the motor and spinning pulley are heavy units, the transporting of the spinner is easily performed whenever the motor and spinner are supported solely upon the wheels. Raising of the motor and spinner onto the wheels is accomplished without any great effort, due to the high leverage ratio resulting from the long handle and the pivoting thereof to the motor base close to the ends carrying the wheels. When the spinner is conditioned for transporting it is quite evenly balanced on the wheels, thus permitting easy pushing and pulling of the

We have disclosed an electric motor driven spinner, but it is believed obvious that other motors can be employed and controlled by the handle in the same manner as has been described with the electric motor.

Being aware of the possibility of modifications in the wheel spinner illustrated and described as embodying our invention, all without departing from the fundamental principles of the invention, we desire it to be understood that the scope of the invention is not to be limited in any manner, except in accordance with the appended claims.

What is claimed is:

1. A portable spinner for rotating a suspended vehicle wheel or the like, comprising, in combination, a base adapted to rest on a support surface, a spinning unit piv-

totally mounted on the base for swinging movement about a generally vertical axis, the spinning unit including a driving motor and a spinning wheel connected to the motor and spaced horizontally from the vertical swinging axis of the unit, a long transport handle swingably connected to the spinning unit, and a pair of retractable transport wheels interconnected with the handle near the pivotal connection of the latter to the spinning unit to be moved downwardly to an operative transport position extending below the base and retracted by vertical swinging movement of the handle in opposite directions, the handle serving as a convenient means for applying high leverage turning force to the spinning unit to carry the spinning wheel horizontally into firm engagement with a wheel to be rotated when the transport wheels have been retracted and the spinner is resting on the base.

2. In a portable heavy duty spinner for rotating a vehicle wheel or the like, the combination of a base adapted to maintain a steady fixed position when rested on a support surface, a spinning unit including a motor and a spinning wheel connected to be rotated by the motor, means pivotally supporting the spinning unit on the base for swinging movement about a generally vertical axis spaced from the center of the wheel, and a long operating handle connected to the spinning unit and having a length several times greater than the spacing between the center of the spinning wheel and the vertical swinging axis of the spinning unit to apply a high leverage turning force to the spinning unit to carry the spinning wheel thereof horizontally into firm engagement with a body to be rotated.

3. A portable heavy duty spinner for rotating a suspended vehicle wheel or the like comprising, in combination, base means adapted to maintain a stationary fixed position when rested on a support surface, a spinning unit including a motor and a spinning wheel connected for rotation by the motor, means pivotally supporting the spinning unit on the base means for swinging movement about a generally vertical axis spaced from the center of the spinning wheel, a long operating handle swingably connected to the spinning unit and having a length several times greater than the spacing between the swinging axis of the spinning unit and the center of the spinning wheel to apply a high leverage horizontal rotatting movement to the spinning unit to carry the spinning wheel firmly into engagement with a wheel to be rotated, at least one transport wheel connected to the handle in spaced relation to the pivotal connection to the latter to be moved vertically into and out of the spinning unit to be moved horizontally into and out of an operative position extending below the base as an incident to reverse vertical swinging movement of the handle, a brake for spinning wheel, and actuating means for the brake coacting with the handle to apply the brake as an incident to predetermined vertical movement of the handle.

4. A portable heavy duty spinner for rotating suspended vehicle wheels and the like, comprising, in combination, a base adapted to maintain a fixed stationary position when rested on a support surface, a spinning unit swingably connected to the base, the spinning unit including a motor and a spinning wheel connected for rotation by the motor and located with its center spaced from the swingable connection of the unit to the base, a vertically swingable transport and operating handle connected to the spinning unit for swinging the unit on the base to carry the spinning wheel firmly against a wheel to be rotated, the handle having a length several times the distance between the center of the spinning wheel and the swingable connection of the spinning unit to the base to provide a high leverage multiplication of manual force applied to the handle as transmitted to the spinning wheel, and retractable transport wheels disposed near the central portion of the spinner and connected with the handle

10 to be moved by the latter toward and away from an operative position extending below the base.

5. A portable heavy duty spinner for rotating a vehicle wheel or the like, comprising, in combination, a base adapted to maintain a steady unmoving position when lowered onto a support surface, a spinning unit mounted on the base for generally horizontal swinging movement about a substantially vertical axis, the spinning unit including a motor and a spinning wheel connected for rotation by the motor and located with its center spaced from the vertical swinging axis of the unit, a vertically swingable transport and operating handle connected to the spinning unit for rotating the latter on the base, the handle having a length several times greater than the spacing between the center of the spinning wheel and the vertical swinging axis of the spinning unit to provide a high leverage multiplication of horizontal force manually applied to the handle as transmitted to the spinning wheel, at least one transport wheel connected to the transport handle for movement thereby into and out of an operative position extending below the base, and releasable latching means for latching the transport wheel in operative position.

20 6. A portable spinner for rotating a suspended vehicle wheel or the like, comprising, in combination, base means adapted to maintain a steady unmoving position when lowered onto a support surface, a spinning unit swingably mounted on the base means and including a motor and spinning wheel connected for rotation by the motor, a swingable transport and operating handle connected to the spinning unit to swing the latter on the base to carry the spinning wheel into engagement with a wheel to be rotated, at least one retractable transport wheel disposed near the central portion of the spinner and connected with the handle to be moved by the latter toward and away from an operative position extending below the base, releasable latching means for latching the transport wheel in operative position, a brake for the spinning wheel, and an actuator for the brake coacting with the handle to apply the brake as an incident to a predetermined swinging movement of the handle.

25 7. A portable heavy duty spinner for rotating a suspended vehicle wheel or the like, comprising, in combination, base means adapted to maintain a steady definite position when lowered onto a support surface, a spinning unit swingably mounted on the base for generally horizontal swinging movement about a generally vertical axis, a vertically swingable handle pivotally connected to the spinning unit for rotating the latter horizontally on the base to carry the spinning wheel thereof into engagement with a wheel to be rotated, retractable transport wheels located near the central portion of the spinner and connected with the handle for movement thereby into and out of operative position extending below the base, releasable latching means coacting with the handle and the spinner unit to latch the transport wheels in operative position, a brake for the spinning wheel, an actuator for the brake coacting with the handle to apply the brake as an incident to predetermined swinging movement of the handle, and control switch means for the motor positioned to be operated by swinging movement of the handle.
